UNITED STATES PATENT OFFICE.

MILTON BOSCACCI, OF OAKLAND, CALIFORNIA.

DESIGN FOR A STATUETTE.

51,671.

Specification for Design.

Patented Jan. 8, 1918.

Application filed October 15, 1917. Serial No. 196,761. Term of patent 3½ years.

To all whom it may concern:

Be it known that I, MILTON BOSCACCI, citizen of the United States, residing at Oakland, in the county of Alameda and State of California, have invented a certain new and ornamental Design for Statuettes, of which the following is a specification.

The figure is a perspective view of a statuette, showing my new design.

I claim :

The ornamental design for a statuette, as shown.

In testimony whereof I affix my signature.

MILTON BOSCACCI.
